UNITED STATES PATENT OFFICE

2,618,226

SIDE CONSTRUCTION FOR RAILWAY
FREIGHT CARS

Arthur J. Doyle, Cleveland, Ohio, assignor to The
Youngstown Steel Door Company, Cleveland,
Ohio, a corporation of Ohio

Application November 5, 1949, Serial No. 125,771

9 Claims. (Cl. 105—409)

1

This invention relates to side constructions for railway freight cars and more particularly to house cars such as refrigerator and box cars.

It is an object of this invention to provide side constructions for railway freight cars which shall obviate the need for coping bottom members utilized to connect the metallic sheathing of the sides to the car underframe.

A further object is to provide sides for railway freight cars which shall eliminate fillers heretofore required, avoid the loss of rivet efficiency occurring when fillers are used and obviate the cost of application of the fillers.

A further object is to provide sides for railway freight cars which shall effect a reduction in the cost of securing the sides to the underframes of the cars.

A further object is to provide sides for railway freight cars which shall embody posts and angle members extending from end to end of the sides and secured to the posts wherein the angle members serve as reinforcement for the sides particularly during shipment and handling and as supports for floors of the cars.

A further object is to provide side constructions particularly adapted for the conversion of wooden sheathed railway refrigerator and box cars to steel sheathed cars wherein the overhang of the constructions beyond the car underframes is small which shall obviate castings and materially reduce costs.

A further object is to provide side constructions particularly adapted for the conversion of wooden sheathed railway refrigerator and box cars to steel sheathed cars which shall provide for direct connection between the posts of the constructions and the car side sills by means of simple and inexpensive pressed brackets.

Other objects of the invention will become clear as the description thereof proceeds.

In the drawings forming part of this specification:

Fig. 1 is an elevation of a railway carside embodying the instant invention, parts being broken away to permit an increase in the scale of this figure.

Fig. 2 is a vertical section taken on line 2—2 of Fig. 1.

Fig. 3 is a vertical section taken on line 3—3 of Fig. 1.

Fig. 4 is a vertical section taken on line 4—4 of Fig. 1.

Fig. 5 is a horizontal section taken on line 5—5 of Fig. 1.

Fig. 6 is a horizontal section taken on line 6—6 of Fig. 1.

2

Fig. 7 is a horizontal section taken on line 7—7 of Fig. 1.

Fig. 8 is a vertical section showing a modified form of connecting bracket.

Fig. 9 is a perspective view of one of the brackets connecting the posts of the carsides to the side sills.

Referring first to Figs. 1 to 7, inclusive, of the drawings, the numeral 10 designates fragmentary portions of a carside construction particularly adapted for railway refrigerator cars. Portions of the carside extending from the door opening to one end of the car are shown, it being understood that the portion of the carside extending from the door opening to the other end thereof is substantially similar in construction. The construction of the carside is substantially the same for both sides of the car.

The carside 10 embodies a side plate 11 to which a roof (not shown) is adapted to be secured. Intermediate posts 12, only one of which is illustrated, door posts, and corner posts such as 13 and 14, respectively, are secured to the depending flange 15 of the side plate which, as is well known, extends substantially from end to end of the car. Metallic sheathing 16 is secured to the depending flange 15 of the side plate and to the door post, intermediate posts and corner posts as is well known. The securing means referred to above may be rivets as shown in the drawings or may be welding if desired.

As shown in Fig. 5 of the drawings, the door post 13 is formed of a Z-shaped member so disposed that its web 17 lies at right angles to the carside, its flange 18 abuts the sheathing 16 and its flange 19 lies inwardly of and in spaced relationship to the sheathing. The intermediate posts 12 are also Z-shaped in cross section and have flanges 20 which are secured to the sheathing 16, an inwardly extending web 21, at right angles to the sheathing and an inner flange 22 spaced from and parallel to the sheathing.

As appears more clearly in Figs. 2 and 4 of the drawings the carside is disposed relative to the side sill 23 of the car underframe so that the posts terminate above the side sill and project outwardly therefrom a short distance. In order to connect the lower margin of the sheathing to the side sill of the car and to close the gap between the sheathing and the side sill a metallic plate 24 which is substantially Z-shaped in vertical section is utilized. The plate 24 extends substantially from end to end of the car and embodies an upstanding leg 25 which lies inwardly of the lower margin of the sheathing 16 and which is secured thereto preferably by means

of rivets. The bottom plate member 24 also embodies an inwardly extending web 26 and a depending leg 27 secured as by means of rivets to the side sill 23.

According to the invention a direct connection between the intermediate and door posts 12 and 13 and the side sill 23 is obtained despite the fact that the overhang or projection of the posts outwardly of the side sill is so small that the brackets normally utilized for this purpose and illustrated in the patent to Ditchfield, 2,201,826, granted May 21, 1940, cannot be employed. The direct connection, moreover, is obtained by means of pairs of inexpensive brackets 28 and 29 which are pressings. The brackets 28 embody angularly related flanges 30 and 31. The flanges 30 terminate above the side sill and are secured to the webs 17 and 21 of the door posts and intermediate posts preferably by means of rivets. The flange 31 is substantially Z-shaped in vertical section and comprises an upstanding leg 32, an inwardly extending web 33 and a depending leg 34. The upstanding leg 32 of each of the brackets 28 abuts the inwardly offset portion 35 of the flange 18 of the door post and the inwardly offset portion 36 of the flange 20 of the intermediate posts. The upstanding leg 32 of each of these brackets is secured preferably by means of rivets to the offset portions of the door and intermediate posts and as well to the upstanding leg 25 of the bottom plate member 24.

The brackets 29 are similarly provided with angularly related flanges 37 and 38. These brackets which are used preferably only with the intermediate posts are so positioned that the flange 37 lies on the opposite side of the web 21 of the intermediate posts and are secured thereto by means of the rivets which fasten the flanges 30 of the brackets 28 to these webs. Flanges 38 are substantially Z-shaped in vertical section and comprise an upstanding leg 39 which abuts and is secured as by means of riveting to the upstanding leg 25 of the bottom plate member, an inwardly extending web 40 and a depending leg 41.

It will be clear from Figs. 2 and 4 of the drawings that the depending legs 34 and 41 of the brackets 28 and 29 lie in contact with the outer face of the side sill 23. Securement of the depending legs 34 and 41 to the side sill which is obtained preferably by means of rivets establishes a direct connection through the brackets between the posts and the side sill. As a consequence of the relationship between the brackets and the side sill, fillers heretofore required between flanges such as 34 and 41 are eliminated. The efficiency of the rivets fastening these legs to the side sill is increased and the expense involved in the required tack welding of fillers to the side sill is eliminated.

In addition to the use of a bracket 28 to secure the door post 13 directly to the side sill, a combined gusset and bracket member 42 disposed on the opposite side of the web 17 from the bracket 28 is employed to further directly secure the door post to the side sill and to reinforce the connection between the door post and the bottom plate member 24. The member 42 embodies angularly related flanges 43 and 44. The flange 43 is secured to the web 17 by the same rivets which secure the flange 30 of the bracket 28 to the web. The flange 43 terminates above the side sill 23. The flange 44 of the combined gusset and bracket member is elongated so that it may be secured directly to the upstand-

ing leg 25 of the bottom plate member against which it abuts as by means of rivets. A portion 45 of this member is substantially Z-shaped in vertical section. This section embodies in addition to the flange 44 an inwardly extending web 46 and a depending flange 47 which lies in contact with the outer surface of the side sill and which is secured thereto as by means of rivets. The need for fillers is avoided in the employment of the combined gusset and bracket member.

As is clearly shown in Figs. 1, 2, 3, 6 and 7 of the drawings, the major portion of the depending leg 27 of the bottom plate member 24 is also directly secured to the outer face of the side sill 23. This is accomplished by offsetting the leg 27 as indicated at 48 around the depending legs 34 and 41 of the brackets 28 and 29 and by offsetting the leg 27 as indicated at 49 around the depending leg 47 of the combined gusset and bracket member 42. In addition to providing direct securement between the depending legs of the bracket members and combined gusset and bracket member to the side sill, the instant invention entirely eliminates the heretofore required coping of the web of the bottom plate member. The strength of this member is thereby maintained. Furthermore, the time and expense involved in welding the copes around the depending legs of the brackets as heretofore required is eliminated.

An angle member 50 which extends substantially from end to end of the car is secured as by means of riveting to the inner flange of the door posts and to the inner flanges of the intermediate posts. The angle member 50 is effective in the loading, unloading and handling of the carside as a unit to strengthen the carside by securely tying the posts together. Moreover, the position of the angle member 50 upon the post is such as to enable it to serve as a support for a portion of the floor 51 of the car, the upper portion of the floor being shown at 51a. The inner lining of the car which terminates above the portion 51a of the floor is indicated at L and the space between the lower edge of the lining and the top of the floor 51a is covered by means of a flexible strip S. A metallic threshold plate is designated generally by the reference numeral P. At the threshold the plate P is inclined upwardly from the outside to the inside of the wall as indicated at U.

The embodiment of the invention illustrated in Fig. 8 of the drawings is applicable where the amount of the overhang or projection of the carside beyond the side sill 52 is somewhat greater than that illustrated in Figs. 2 and 3 of the drawings. In this embodiment the bottom plate member 53 which is formed with an upstanding leg 54 and a depending leg 55 is provided with a somewhat deeper web 56 arranged relative to the posts and metallic sheathing in the manner heretofore described. The depending leg 55 is offset as indicated at 57, in order to provide for direct engagement and securement of the depending leg 58 of a modified bracket 59 directly to the outer face of the side sill 52.

The bracket 59 similar to the brackets heretofore described is adapted to be secured on opposite sides of the webs of the intermediate posts and to one side of the web of the door post. It embodies in addition to the depending leg 58 an upstanding leg 60 and an angularly related flange 61 through which the bracket is secured to the webs of the posts. The bracket 59 also

comprises a web 62 which preferably slopes downwardly and inwardly from the upstanding leg 60 and is integral therewith and with the flange 61. By this construction the bracket 59 lends itself readily to production as a pressing. The attributes heretofore set forth of the brackets 23 and 29 are found as well in the bracket 59.

It will be apparent that numerous changes and modifications in the details of the invention will be clear to those skilled in the art. It is intended, therefore, that all such modifications and changes be comprehended within this invention which is to be limited only by the scope of the claims appended hereto.

I claim:

1. A side construction for a railway car comprising a metallic side plate, metallic intermediate and door posts secured to said side plate, metallic sheathing secured to said side plate and to the outer face of said posts, a substantially Z-shaped bottom plate member having an upstanding leg secured to the outer face of said posts, a web extending inwardly below said posts and a downwardly extending leg, said sheathing being secured along its lower margin to said upstanding leg of said bottom plate member, and brackets secured to said posts on opposite sides thereof, each of said brackets having an inwardly extending flange secured to a post and an angularly related substantially Z-shaped flange embodying a downwardly extending leg, said downwardly extending leg of said bottom plate member being offset outwardly around said downwardly extending legs of said brackets, said side construction being positioned relative to a side sill of said car so that said posts terminate above and project outwardly of said side sill and said downwardly extending legs of said bottom plate member and brackets lie outwardly of said side sill for direct securing thereto.

2. A side construction for a railway car comprising a metallic side plate, metallic intermediate and door posts secured to said side plate, metallic sheathing secured to said side plate and to the outer face of said posts, a substantially Z-shaped bottom plate member having an upstanding leg secured to the outer face of said posts, a web extending inwardly below said posts and a downwardly extending leg, said sheathing being secured along its lower margin to said upstanding leg of said bottom plate member, and brackets secured to said posts on opposite sides thereof, each of said brackets having an inwardly extending flange secured to a post and an angularly related substantially Z-shaped flange embodying a downwardly extending leg, said downwardly extending leg of said bottom plate member being offset outwardly around said downwardly extending legs of said brackets, said side construction being positioned relative to a side sill of said car so that said posts terminate above and project outwardly of said side sill and said downwardly extending legs of said bottom plate member and brackets lie outwardly of and in abutment with said side sill for direct securing thereto, said downwardly extending legs of said brackets projecting below said bottom plate member.

3. A side construction for a railway car comprising a metallic side plate, metallic intermediate and door posts secured to said side plate, metallic sheathing secured to said side plate and to the outer face of said posts, a substantially Z-shaped bottom plate member having an upstanding leg secured to the outer face of said posts, a

web extending inwardly below said posts and a downwardly extending leg, said sheathing being secured along its lower margin to said upstanding leg of said bottom plate member, and brackets secured to said posts on opposite sides thereof, each of said brackets having an inwardly extending flange secured to a post and an angularly related flange having a portion extending downwardly below said inwardly extending flange, said downwardly extending leg of said bottom plate member being offset outwardly around said downwardly extending portions of said angularly related bracket flanges, said side construction being positioned relative to a side sill of said car so that said posts terminate above and project outwardly of said side sill and said downwardly extending leg of said bottom plate member and said portions of said angularly related flanges of said brackets lie outwardly of and in abutment with said side sill for direct securing thereto.

4. A side construction for a railway car comprising a metallic side plate, metallic intermediate and door posts secured to said side plate, metallic sheathing secured to said side plate and to the outer face of said posts, a substantially Z-shaped bottom plate member having an upstanding leg secured to the outer face of said posts, a web extending inwardly below said posts and a downwardly extending leg, said sheathing being secured along its lower margin to said upstanding leg of said bottom plate member, and brackets secured to said posts on opposite sides thereof, each of said brackets being a pressing and having an inwardly extending flange secured to a post and an angularly related substantially Z-shaped flange embodying a downwardly extending leg, said downwardly extending leg of said bottom plate member being offset outwardly around said downwardly extending legs of said brackets, said side construction being positioned relative to a side sill of said car so that said posts terminate above and project outwardly of said side sill and said downwardly extending legs of said bottom plate member and brackets lie outwardly of and in abutment with said side sill for direct securing thereto.

5. A side construction for a railway car comprising a metallic side plate, a metallic door post secured to said side plate, a bracket secured to one side of said door post, and a combined gusset and bracket member secured to the opposite side of said door post, said member having a substantially Z-shaped flange embodying a web extending inwardly below said door post and a downwardly extending leg, said side construction being positioned relative to a side sill of said car so that said post terminates above and projects outwardly of said side sill, said bracket being adapted to abut and be secured directly to said side sill, said leg lying outwardly of and in abutment with said side sill for direct securing thereto.

6. A side construction for a railway car comprising a metallic side plate, a metallic door post secured to said side plate, a bracket secured to one side of said door post, and a combined gusset and bracket member secured to the opposite side of said door post, said member having a substantially Z-shaped flange embodying a web extending inwardly below said door post and a downwardly extending leg, said side construction being positioned relative to a side sill of said car so that said post terminates above and projects outwardly of said side sill, said bracket being

adapted to abut and be secured directly to said side sill, said leg lying outwardly of and in abutment with said side sill for direct securement thereto, said side construction also comprising a bottom plate member extending substantially from end to end thereof secured to the outer face of said door post, said plate member extending downwardly so as to lie outwardly of said side sill for abutment and direct securement thereto, said plate member being offset outwardly around said leg, said gusset and bracket member being secured to the inner face of said plate member above the bottom of said door post.

7. A side construction for a railway car comprising metallic posts, a bottom plate member secured to the outer face of said posts, and pairs of brackets secured to opposite sides of said posts, each of said brackets having a portion extending inwardly below said posts and a downwardly extending leg, said plate member being offset outwardly around said downwardly extending legs, said side construction being positioned relative to a side sill of said car so that said posts terminate above and project outwardly of said side sill and said plate member and downwardly extending legs of said brackets lying outwardly of and in abutment with said side sill for direct securement thereto.

8. A side construction for a railway car comprising metallic posts, a bottom plate member secured to the outer face of said posts, and pairs of brackets secured to opposite sides of said posts, each of said brackets having a portion extending inwardly below said posts and a downwardly extending leg, said plate member being offset outwardly around said downwardly extending legs, said side construction being positioned relative to a side sill of said car so that said posts ter-

minate above and project outwardly of said side sill and said plate member and downwardly extending legs of said brackets lie outwardly of and in abutment with said side sill for direct securement thereto, and a member secured to the inner face of said posts below the position to be occupied by the floor of said car, said latter member tying said posts together and being adapted to serve as a support for the car floor.

10. 9. A side construction for a railway car comprising metallic posts, a bottom plate member secured to the outer face of said posts, said plate member extending inwardly below said posts and then downwardly, and brackets secured to opposite sides of said posts, each of said brackets being formed of a pressing and having an inwardly extending flange secured to a post and an angularly related substantially Z-shaped flange, said latter flange having an upstanding leg, an inwardly extending web and a leg extending downwardly from said web, said web being integral with said inwardly extending flange of said bracket, said plate member being offset outwardly around said downwardly extending legs of said brackets.
